 SWIMMING POOL AND METHOD FOR ERECTING
SAME

Leo Lucchesi, Chicago, Ill.

Filed Dec. 27, 1956, Ser. No. 630,844

6 Claims. (Cl. 50—100)

This invention relates in general to storage vessels and in particular to swimming pools and a method for erecting same.

A well known method of constructing an open-type vessel embedded in earth, such as a swimming pool, is to excavate a suitable opening in the earth, erect a shell or mold of suitable material to define a space between the earth and the shell, and pour a form-setting material, such as cement, into the space. After the poured material has set, the shell is removed and the vessel made of the form-setting material is then available for use. This type of construction is time consuming and expensive with the result that prefabricated swimming pools, which are assembled at the site of installation, are finding a popular following. Prior to the installation of a prefabricated pool, a suitable excavation is made in earth, slightly larger than the pool. The pool is then assembled piece by piece within the excavation. Inasmuch as the pool is supported by the earth and serves essentially as a liner to prevent absorption of water by the earth, it is constructed of thin sheath material, such as metal or plastic material. Therefore, it is imperative that a firm foundation afforded by earth exist immediately adjacent the pool structure, otherwise, the pool, in places of non-support, will be stressed beyond the yield point of the fabricated material and will deform with possible subsequent rupture. The conventional type of prefabricated pool usually comprises vertical walls which curve inward toward the center of the pool to form a rounded bottom, the pool having a predominantly flat bottom in the central portion thereof. During the installation of the pool within the excavation, it is relatively simple to direct proper fill adjacent to the vertical wall sections of the pool to provide a firm backing, but it is extremely difficult to obtain proper support underneath the bottom of the pool, said bottom of the pool supporting practically the entire body of the water when filled.

It is the object of this invention to provide a method for installing a pool having a firm and proper foundation thereunder.

Another object of the invention is to provide a pool which can be assembled easily with proper fill underneath.

Another object of the invention is to provide means for containing fluids in an excavation, said means serving as a liner to prevent absorption of the fluid by the excavation and having a bottom portion adapted for facilitating obtaining a firm foundation therefor.

Further objects and advantages of the present invention will be apparent to those skilled in the art upon the perusal of the specification in conjunction with reference to the following drawings, wherein:

FIGURE 1 is a plan view of a swimming pool having incorporated in the bottom thereof insertable bottom members for facilitating erection;

FIGURE 2 is a longitudinal section view of the swimming pool taken along the line 2—2 of FIG. 1;

FIGURE 3 is a transverse section view of the swimming pool taken along the line 3—3 of FIG. 2;

FIGURE 4 is an enlarged fragmentary view of a section of the swimming pool taken along the line 4—4 of FIG. 1;

FIGURE 5 is a cross section view along the line 5—5 of FIG. 4 to show the structure of a joint;

2

FIGURE 6 is an enlarged fragmentary view of a section of the swimming pool taken along line 6—6 of FIG. 1 to show the details of assembly;

FIGURE 7 is an enlarged fragmentary view of a joint between two structure members, taken along the line 7—7 of FIG. 1; and

FIGURE 8 is an enlarged fragmentary view of a joint between two structure members taken along the line 8—8 of FIG. 1.

10 In accordance with the teachings of this invention there is provided a method of erecting a shell-type vessel, such as a swimming pool, in an excavation in earth. The vessel is erected from prefabricated wall members which are assembled together in the excavation in such manner that an enclosure is erected having at least one opening in the bottom thereof presenting an access to the bottom of the excavation. Since it is essential that the erected vessel have a solid foundation to rest upon, suitable material is filled into the excavation around the enclosure. To obtain a solid foundation for the bottom of the vessel, material is filled through the opening in the bottom of the vessel and tamped, and finally, the opening is completed to effect a fluid-tight vessel. Essentially, the method of erecting a vessel comprises initiating the wall structure and building downward to complete the bottom of the vessel.

Furthermore, in accordance with the teachings of this invention there is provided a vessel structure adapted to be erected in an excavation in earth. The vessel is erected from preformed wall members which have curved sections sloping downward and toward the centrum of the vessel to define an opening therebetween adapted to admit an insertable bottom member. The members defining the opening have depressed flanges adapted to support the bottom member at the same level as the surrounding members. Suitable means are provided for rigidly securing the members in the spaced apart relationship to provide the opening which is completed by the bottom members.

If reference be had to FIGURES 1, 2 and 3, an open-type vessel 26, such as a swimming pool, is shown erected in an excavation 28 in earth. The vessel 26 comprises wall members 30 specifically designated as 30a, 30b, 30c, 30d, 30e, 30f, 30g, 30h, 30i, 30j, 30k and 30l and bottom members 54 specifically designated as 54a, 54b, and 54c.

The bottom members 54a and 54b, called insertable bottom members, are adapted to be placed centrally in the bottom of the vessel 26 during the final stages of erection, as will be described later. The stationary bottom member 54c is disposed centrally in the bottom of the vessel 26 and couples together the two bottom members 54a and 54b. The stationary bottom member 54c is permanently attached at two of its opposing sides to the wall members 30f and 30g.

55 Each wall member 30, such as the wall member 30e, as shown in FIGURES 4 and 5 comprises a thin wall 60 which terminates laterally in a flange 62 and forms at top thereof a coaming 64. The flange 62 extends exterior to the vessel 26 so that a smooth uninterrupted interior surface is obtained within said vessel. Each wall member 30 has a straight section 55, which forms the vertical side of the vessel 26, and a convex on curved section 56 which slopes downward and toward the bottom centrum of the vessel 26. The wall members 30 are constructed of any suitable material, preferably material which does not corrode upon contact with fluids such as water. Furthermore, the material preferably has to be amenable to mold fabrication to obtain desired shapes and contours in the fabricated structures. For example, the wall members 30 may be constructed of several plies of synthetic fiber or

60 glass cloth impregnated and combined together with a resin or plastic binder such as polyester, phenolic or poly-

styrene. The adjoining wall members, such as 30c and 30e, are secured to each other by bolt-nut assemblies 66 which include washers 68 on both sides of the coupled flanges 62 to prevent gouging by said bolt-nut assemblies. Prior to bringing the flanges 62 to mate with each other, a layer of sealing compound 70 or resin is spread on the mating surfaces to obtain a fluid-tight joint after the bolt-nut assemblies 66 are tightened.

The wall member 30b has an opening 72 in the straight section 55 thereof for admitting a sealed lamp 76 connected to an electrical conduit 78 which may be connected to a source of electrical power. The lamp 76 provides underwater illumination. The wall member 30k has an opening 80 in its straight section 55, which opening may be connected through a pipe 82 to an overflow drain for maintaining constant the level of the water in the vessel 26. The bottom member 54a has an opening 84 adjacent to a screened drain 86 which is connected to a drain pipe 88 used for draining the water out of the tank 26.

As was brought out earlier in reference to the method of erection of the vessel, certain bottom members, namely 54a and 54b, are installed during the final stage of erection. The wall members 30b, 30d and 30e together with the stationary bottom member 54c define an opening 58a therebetween for admitting the insertable bottom member 54a. Similarly, the wall members 30h, 30i and 30k together with the stationary bottom member 54c define an opening 58b therebetween for admitting the insertable bottom member 54b.

If reference be had to FIGURES 6, 7 and 8, the manner of support of the bottom members 54a and 54b is indicated. The wall members 30b and 30k together with the stationary bottom member 54c have depressed extensions 94 adapted to support the insertable bottom members 54a and 54b on the same level as the abutting wall members. Similarly, the wall members 30d, 30e, 30h and 30i have depressed extensions 96 for supporting the bottom members 54a and 54b. The extensions 96 terminate in vertically disposed flanges 98 which have openings 100 for admitting studs 102 adapted to span across the opening between two oppositely disposed wall members 30, such as 30d and 30e. The studs 102, nuts 104 and washers 106 serve to maintain a rigid opening between the oppositely disposed wall members 30 so that there will be no outward movement away from the center of the vessel 26 when it is filled with water. The insertable bottom members 54a and 54b are secured to the depressed flanges 94 and 96 by self-tapping screws 108. The joints between the mating surfaces of the bottom members 54a and 54b and the depressed flanges 94 and 96 are filled with a sealing compound 110 to insure a fluid-tight joint. The sealing compound 110 is also used to cover the heads of the screws 108 and to effect a smooth covering over the assembly joints to present the appearance of a single continuous surface on the interior of the vessel 26. It is to be understood that although only two bottom members 54a and 54b have been described in the present embodiment of the invention as being insertable in the final stage of erection of the vessel 26, additional bottom members can be made insertable near the end of erection, if it is found to be desirable.

The method of erection of the various structural components comprising the vessel 26 will be briefly described hereinbelow. The erection is commenced in an excavation 28 which is larger than the size of the intended vessel 26 to permit freedom of movement during assembly. The assembly work is usually started at the deep end of the excavation with the assembly of the wall members 30a, 30b and 30c by introducing the sealing compound 70 between the mating surfaces of adjoining flanges 62 and drawing them together with bolt-nut assemblies 66 to effect fluid-tight joints. Since the wall members 30 are fabricated of comparatively low density material, some of the assembly work can be performed outside of the excavation 28 and then lowered into said excavation. For example, the wall members 30f, 30g and the bottom

member 54c may be assembled exterior to the excavation and then introduced thereafter as an integral unit into the excavation to be coupled with other, already erected members, thus expediting erection of the vessel

5 26. During the time of erection when the wall members 30d and 30e, as well as 30h and 30i, are disposed opposite each other in the excavation 28, studs 102 are inserted through the openings 100 in the flanges 98 of said 10 oppositely disposed wall members to provide rigidity between the members even though openings 58a and 58b 15 exist therebetween for the admission of the insertable bottom members 54a and 54b, respectively.

At the final stage of erection, the wall members 30a, 30b, 30c, 30d, 30e, 30f, 30g, 30h, 30i, 30j, 30k and 30l 20 together with the stationary bottom member 54c define a shell-type enclosure having an incomplete bottom presenting the two openings 58a and 58b. Any suitable material such as sand is filled into the excavation 28 adjacent to the exterior of the straight sections 55 and the 25 convex sections 56 of the wall members 30 to provide a solid foundation. The two openings 58a and 58b in the bottom of the vessel 26 which are adapted to receive the insertable bottom members 54a and 54b, respectively, are utilized for filling sand under the rounded bottom of the 30 vessel 26 to provide a solid foundation under the lowermost portions of the convex sections 56. Finally, the sand is tamped to proper height in the bottom openings 58a and 58b to provide a firm support for the insertable bottom members 54a and 54b. Then the bottom members 35 54a and 54b are placed over the bottom openings, 58a and 58b, respectively, with a sealing compound 110 between the mating surfaces and secured with the screws 108. Thereafter, the sealing compound 110 is applied over the various assembly joints to conceal the screws and 40 to present a continuous surface. A cement walk 112 is constructed about the vessel 26 in abutting relationship to the coaming 64, said cement walk being adapted to support a ladder 114 introduced into the interior of the vessel 26.

What is claimed is:

1. A prefabricated swimming pool adapted to be assembled in an excavation, comprising, in combination, a plurality of straight and curved wall members constructed of low strength material and disposed rigidly in relation to each other to form an open bottom enclosure, some of the straight and curved wall members oppositely disposed to each other being shorter than the others, said shorter straight and curved wall members sloping downward and inward toward each other with their edge portions defining an opening therebetween in the bottom of said enclosure, said edge portions having depressed extensions which cooperatively define a bezel, means for maintaining oppositely disposed extensions in a predetermined rigid relation to each other, and a detachable means supported by the depressed extensions and cooperatively defining with the bezel a fluid-tight bottom enclosure to provide access underneath the pool.

2. A swimming pool as claimed in claim 1, said means for maintaining the predetermined rigid relation of the flanges comprising elongated rod members extending 60 through substantially vertical flange walls of the oppositely disposed edge portions, said rod members having threaded ends with nuts abutting against the flange walls exteriorly of the bottom enclosure.

3. A prefabricated sectional vessel comprising, in combination a plurality of straight and curved wall members constructed of low strength material and positioned side-by-side, some of the straight and curved wall members oppositely disposed to each other being shorter than the others, said straight and curved wall members sloping downward and inward and defining an opening therebetween at the bottom of the vessel, the straight and curved wall members terminating in edge portions having substantially horizontal and substantially vertical flanges, the horizontal flanges defining therebetween a support for an insertable and removable bottom member closing said

opening, threaded spacing members, individually adjustable, disposed between oppositely facing vertical flanges for maintaining the associated wall members in rigid disposition, and means for detachably securing the bottom member to the horizontal flanges to provide a fluid-tight seal.

4. A prefabricated swimming pool adapted to be assembled in an excavation, comprising in combination, a plurality of preformed wall members constructed of low strength material and arranged alongside of each other, each wall member having a straight and curved section, the wall members having lateral flanges extending outwardly of the wall members, means for securing adjacently disposed flanges exteriorly of the wall members, said curved sections sloping downward and inward toward each other with their lowermost edges defining an opening therebetween in the bottom of the pool, said edges having depressed portions cooperatively defining therebetween a seat, said depressed portions terminating in substantially vertical flanges, rod members adjustably extending through the flanges for maintaining rigid relationship therebetween, and a removable plate supported by the depressed portions and cooperatively defining therewith a fluid-tight bottom enclosure but permitting access thereunder.

5. A swimming pool according to claim 4, said preformed wall members comprising at least three groups of sections having predetermined symmetric relationships, one group forming arcuate corners of the pool, the second group forming transverse and longitudinal sides of the pool, and the third group forming the bottom of the pool, the size of the pool being determined by the plurality of the members used in the second and third groups.

6. A method of assembling a prefabricated vessel in an excavation, said vessel being made of material of low strength, comprising the steps of making a rough excav-

tion for substantially containing the vessel, attachably disposing preformed straight and curved wall members adjacent each other to form substantially a complete enclosure with a small opening in the bottom thereof rigidifying the opening exteriorly of the wall members to predetermined dimensions, filling material exteriorly of the wall members to effect sound foundation therefor, filling material through said opening and tamping said material underneath the bottom-most portions of the wall members, filling the opening to substantially the level of the bottom-most portions of the wall members, and detachably securing a bottom member to the bottom-most portion of the wall members to effect a fluid-tight closure of the opening thereby providing access to the underneath of the bottom of the vessel at all times.
